CLAIM

The ornamental design for an armoire, as shown and described.

DESCRIPTION

FIG. 1 is a front view of an armoire, showing our new design;

FIG. 2 is a side elevational view, the opposite side being a mirror image thereof;

FIG. 3 is a top plan view thereof; and,

FIG. 4 is a rear elevational view thereof.

The portions of the article not shown in the drawing or described in the specification form no part of the claimed design.
